(57) **CLAIM**

The ornamental design for an auxiliary arm carrier support for a screen printing platen, as shown and described.

DESCRIPTION

FIG. 1 is a front elevation view of an auxiliary arm carrier support for a screen printing platen showing my new design, attached to a movable carrier support for a screen printing platen, the movable carrier support not forming part of this invention;

FIG. 2 is a top plan view thereof;

FIG. 3 is a bottom plan view thereof;

FIG. 4 is a left side elevation view thereof;

FIG. 5 is a right side elevation view thereof;

FIG. 6 is a rear elevation view thereof; and,

FIG. 7 is a perspective view thereof.
